DRAFTING BOARD

Melville P. Hite, Jacksonville, Fla.

Application December 7, 1948, Serial No. 63,963

1 Claim. (Cl. 45—131)

1

This invention relates to drafting boards on which a sheet of paper or other material is fastened and on which drawings are made, aided by certain guiding means along the edges of which lines may be drawn. Customarily such guiding means are not fastened and receive primary orientation from a principal guiding aid which has a flange-like portion and a straightedge portion disposed at an angle to said flange-like portion. Customarily an edge of the board is adapted to form a straightedge element and through the said flange-like portion the principal guiding aid receives primary orientation from said straightedge element, which in turn is communicated to other guiding aids. It may be observed that the straightedge element formed by the edge of the board is below the surface of the board and hence out of contact with the surface thereof and hence out of contact with a sheet of paper or other material upon said board surface. It may be further observed that the principal guiding aid because of its flange-like projection combined with a straightedge portion is a rather bulky or clumsy object to use or transport.

In my invention a straightedge element for primary orientation is positioned above the plane of the surface of a board element and is substantially in contact with said surface throughout its length hence the said straightedge element is also in substantial contact with a portion of a sheet of paper or other material imposed on the surface of said board element. In my invention the straightedge element is removably fixed in position and held there by clamping means which exercise a wedgelike action when actuated by slidable motion between said straightedge element and said board element. The said clamping means of my invention also operate to removably clamp and hold a sheet of paper or other material when said clamping means are operated by said slidable motion. Elements of said clamping means also furnish guides for positioning a sheet of paper or other material on the surface of said board element. The clamping means of my invention include means for adjusting the force of the clamping action. It is obvious that the straightedge element positioned above the surface of the board element in my invention has an edge which in effect forms an upwardly projecting flange along which guiding aids may be oriented, hence a primary guiding aid including a flange-like straightedge portion is not necessary and all the guiding aids used may be such as have their bodies substantially in the plane of the surface of the board element. In this form the

guiding aids are more convenient for use and are readily transportable when nested against the retaining barrier of the straightedge element, thus the board element with straightedge element attached and certain guiding aids form a neat and readily transportable parcel. In accord with the above it is a special object of my invention to provide a form of drafting board having protective space within the limits of the board itself for accommodation of guiding aids, briefly a less bulky, neater, more compact form of drafting outfit.

Another object of the invention is to provide a more rapid and efficient means for positioning and fastening a sheet of paper on the surface of a drafting board. In my construction this object is attained by loosening or removing the straightedge element through slidable motion, then placing a sheet of paper against the guides formed by parts of the clamping means, restoring the straightedge element and by slidable motion securely clamping both the straightedge element and the sheet of paper by slidable motion. By my construction a push at one end of the straightedge element clamps it and the sheet of paper while a push at the other end unclamps both. By experiment I have found that small sheets, say conventional letter size, about eight by ten inches, tend to lay flat against the board surface when held securely along one edge of the paper by the straightedge element. With larger sheets additional fastenings may be added by means of "Scotch tape," tacks, etc. It is accentuated that the straightedge element has a dual capacity in that it is a primary means for orientation of guiding aids and that it is also a clamping element for securing the paper in fixed position.

It is a further object of my invention to provide a drafting board requiring the use of only such drafting guiding aids as have their bodies and edges substantially in the plane of the surface of the board element.

My invention may include a plurality of clamping means or require only a single clamping means slidably operated. If the straightedge element acts about the axis of a single clamping means it may be rotated to, substantially, any axial position parallel with the surface of the board element and there serve both as a guiding aid for orientation and also as a fastening for the paper. Accordingly it is another object of my invention to provide a drafting board having a straightedge element rotatable in the plane of the surface of said board element.

It is another object of my invention to provide a drafting board whereon drafting guiding aids may

be more rapidly and certainly positioned in axial alignment and manipulated in orientation.

These and other objects will more fully appear in the following description of my invention accompanied by the drawings wherein:

Fig. 1 is a top view of the assembled parts with a sheet of paper indicated in position and with two triangle guiding aids also shown.

Fig. 2 is a view in side elevation with a portion of the base member and straightedge in section.

Fig. 3 is a view in end elevation.

Fig. 4 is a view similar to Fig. 1 but with the straightedge and triangle guiding aids shifted angularly relative to the edges of the base member.

Fig. 5 is a detailed view of one end of the straightedge and a modified means for clamping it to the base member.

Fig. 6 is a view taken on line 6—6 of Fig. 5.

Fig. 7 is a view taken on line 7—7 of Fig. 5.

Fig. 8 is a detailed view of one end of the straightedge and illustrating a modified form of means for clamping it to the base member.

Fig. 9 is a view taken on line 9—9 of Fig. 8.

Fig. 10 is a detailed view of one end of the straightedge and illustrating a further type of means for clamping it to the base member.

Fig. 11 is a view taken on line 11—11 of Fig. 10.

Fig. 12 is a view taken on line 12—12 of Fig. 10.

In the embodiment of the invention illustrated in Figs. 1, 2, 3 and 4 I have provided a base member designated by the numeral 1. This base member may be formed of any suitable substantially rigid material to present a flat surface for supporting paper and the like adapted to be written, drawn or otherwise worked on. Removably mounted on the upper working flat surface of the base member is a straightedge element 2 which may consist of a strip of wood or other suitable material of sufficient strength to provide the necessary rigidity. As will become apparent as this description of my invention proceeds one or more strips of paper 3 are clamped along one edge between the straightedge and the base member so that the paper is substantially immovably positioned relative to the base member. A common drafting triangle 4 is illustrated positioned and oriented against the upwardly extending flange like edge of the straightedge element 2. It will be recognized that the triangle 5 takes orientation from the triangle 4. It will be understood that the guiding aids provided by the triangles may be moved along said straightedge and retain orientation, and also those guiding aids may be combined otherwise and with other guiding aids and that all may take primary orientation from the upwardly projecting flange like edge of said straightedge element 2.

The straightedge element 2 is reciprocally as well as removably mounted on the base member 1 so that it may be moved from position clamping one or more papers between it and the base member and to unclamping position. The means for selectively clamping and unclamping the straightedge to the base member includes a recess 6 formed through the straightedge and a bifurcated inclined plane or opposed spaced apart inclined shoulders 8. It will be apparent from the drawings that the shoulders 8 do not extend the full length of the recess so that an opening 8' is provided which is wider than the space between the shoulders 8. I provide a straightedge retaining means in the form of a screw 9 which is screwed into the base member in such a manner that it projects angularly therefrom. The screw

includes a head rigidly formed with the shank of the screw so that the undersurface of the head of the screw presents an inclined plane surface 9'. It is preferable that the angle of inclination of the surface 9' on the under side of the screw head to the perpendicular be substantially equal to the angle of inclination of shoulders 8 to the horizontal.

When the straightedge is operatively positioned 10 on the base member the screw 9 projects into the recess 8 in the straightedge and the head of the screw projects above the shoulders 8 so that the inclined plane surface 9' of the head is in position to ride up on the inclined plane 8. The wide 15 opening 8' permits the straightedge to be removably attached to the base member for the head of the screw may pass through the wide opening.

When the straightedge is reciprocated relative to the base member by slidable motion the inclined plane or surface 9' on the lower surface 20 of the screw head will reciprocally cooperate with the inclined plane or shoulders 8 and these inclined planes tend to engage or disengage to produce a wedge like clamping action between 25 straightedge 2 and base member 1. The incline of the inclined planes being quite flat a small rotation of the straightedge about the vertical axis of the screw does not sensibly decrease the effect 30 of the clamping action, though a larger rotation greater than that indicated in Fig. 4 tends to render it ineffective. Rotation of the straightedge element establishes new axes of primary orientation for guiding aids and has considerable value in practice.

35 It is obvious that a plurality of such clamping means as is above described may be provided, and two such are shown in Fig. 1. The purpose of a plurality is to extend the clamping action effect on the edge of a sheet of paper, and, also to 40 provide a fixed axial alignment for the straightedge element 2. The bodies of a plurality of screws form guides for the axial alignment of a sheet of paper or other material. Thus with a plurality as described the sheet of paper may be held to a certain orientation while the straightedge element 2, may be rotated to various positions and later returned to its original position, whence lines related to many different axes may be drawn on the same sheet of paper.

45 In the embodiment of my invention illustrated in Figs. 5, 6 and 7 I have used the same reference numerals to describe similar parts. In this form of my invention I have departed from the form shown in Figs. 1 through 4 only by using a substantially flat or philister screw head 10 having a tapered underhead 11 which rides on the inclined planes provided by shoulders 8 on the straightedge. Thus, the inclined planes engage with a very small contact area and along substantially vertical axial areas. The effect of this is to permit rotation of the straightedge element 2 to practically any angle without much reducing the effect of the clamping action.

50 In either of the above described embodiments of my invention it is obvious that the screws offer a ready means of adjusting the effect of the clamping action. It is also obvious that when moved to the limit the straightedge element may be lifted free from the board element and readily 55 restored to its form position. It is also within my contemplation in certain adaptations of my invention to reverse the parts, that is the screw would project from the straightedge into a recess providing inclined shoulders which would be formed in the base member.

In Figs. 8 and 9 I have illustrated a further form of my invention, and for similar parts to those used in the form shown in Figs. 1-4 I have used the same reference characters. The straight-edge is formed with a recess 6 and a tongue or the like 12 projects into the recess from an end wall thereof. This tongue is formed with an inclined upper surface 13 adapted to function in generally the same way as the shoulders 8 in the prior described forms of my invention. A suitable spring element 14 is fastened to the base member 1 and is adapted to project therefrom into the recess 6. The spring element includes a projecting portion 15, the under surface of which is adapted to form an inclined plane reciprocal to and cooperating with the inclined plane formed by the upper surface 13 of tongue 10. Thus, slidable motion between straightedge 2 and base member 1 effects a wedge like clamping action, clamping or unclamping the straightedge and base and also any part of a sheet of paper between them. The rising part 16 of spring element 14 forms a positive guide for positioning a sheet of paper.

In Figs. 10, 11 and 12 I have illustrated a further form of my invention. In this form the wedge like clamping action between the straight-edge and the base member occurs between a suitably undercut body 17 which is rotatably secured to the base member 1 by a single screw, rivet or the like 18' and the body 17 is adapted to project into recess 6 formed in straightedge 2. The body 17 is of tapering or wedge like construction presenting a narrow end 18 and a wide end 19. The recess 6 is of tapering form complementary to the shape of body 17 and the walls 20 of the recess are inclined inwardly and downwardly to properly coact with the undercut sides of the body. Thus, the straightedge element 2 may be rotated to any angle without effecting the 40

The forms of my invention illustrated in Figs. 8 thru 12 also provide for removal of the straight-edge from the base member.

Having described my invention, I claim:

- 5 A drafting board, including a base member, a straightedge element removably attached to said member, said straightedge element having slots therein, retaining means rigidly attached to said member and projecting therefrom at an acute angle thereto and extending through the slots, enlarged heads rigidly fixed on the ends of the retaining means which extend through the slots, said heads having inclined plane surfaces thereon, and complementary inclined plane surfaces on said straightedge element positioned thereon for wedging engagement with the inclined plane surfaces on said heads to clamp said straightedge element to said base member by a sliding movement of said straightedge element relative to said base member, and said slots being widened at one end to permit passage of said heads therethrough, whereby said straightedge element may be removed from said base member.

MELVILLE P. HITE.
